UNITED STATES PATENT OFFICE.

LEONIDAS E. JEFFERSON, OF BALTIMORE, MARYLAND.

ROPE GUIDE.

Application filed October 19, 1923. Serial No. 669,620.

To all whom it may concern:

Be it known that I, LEONIDAS E. JEFFERSON, a citizen of the United States, residing at Baltimore, in Baltimore city and State of Maryland, have invented certain new and useful Improvements in Rope Guides, of which the following is a specification.

My invention relates to an improvement in rope guides.

The object is to provide a device of the character named or especially adapted for use in connection with awnings and the invention consists in three parts, namely, a main plate with fastening spurs on the end and having a loop or eyelet at the center, a shop guide pivoted or swiveled therein, and a clamping plate between which and the main plate the awning material is received.

In the accompanying drawings:

Figure 1 is a view in perspective showing the rope guide attached to a piece of awning material;

Figure 2 is a perspective view showing the clamping plate slightly removed from the main plate;

Figure 3 is a longitudinal section;

Figure 4 is a transverse section; and

Figure 5 shows the blank from which the main plate and spurs are formed.

A represents a piece of awning or other fabric. 1 is the main plate having two slits 2 cut crosswise therein as shown in Figure 5 and the intermediate portion is struck up to form a loop or eyelet 3. At the ends sharp-pointed spurs 4 are formed. These spurs are adapted to pierce the fabric A and extend through the slots 5 in the clamping plate 6 and be bent inwardly as shown in Figure 1, thus clamping the main plate securely to the awning fabric.

The rope guide 7 is rounded transversely as at 8 to form a smooth and rounded bearing for the awning rope 9 as shown in Figure 4 and the ends 10 of the guide are bent inwardly in the form of pintles which enter the opposite ends of the loop or eyelet 3 and turn or swivel freely therein.

In this way a simple device of few parts

is formed which is easily attached to the awning and which forms a yielding and effective guide for the awning rope, which latter is guided and supported and rendered slidable therein.

55

I claim:

1. A device of the character described including a main plate and clamping plate one of which has spurs and the other openings to receive said spurs after which they are bent to clamp the plates on opposite sides of the material to which the device is secured, one of said plates having an open-ended loop or eyelet and a guide having its ends extending into the opposite ends of the loop or eyelet whereby the guide is pivoted or swiveled to the plate.

60

2. A device of the character described including a main plate, a guide pivoted or swiveled for oscillation with respect to said plate and a clamping plate between which and the main plate the material to which the device is secured is held, and means for fastening the two plates and the interposed material securely together.

70

3. A device of the character described including a main plate having transverse slits and the intermediate portion of the plate struck up to form an open ended loop or eyelet between the slits, the ends of the main plate terminating in pointed spurs, a guide having its ends in the form of pintles extending into and pivotally mounted in the ends of the loop or eyelet, a slotted clamping plate, the slots of which are adapted to receive the spurs of the main plate whereby to fasten the device securely to the material to which it is to be applied.

75

4. A device of the character described including a main plate and a clamping-plate, means co-operating with the plates for clamping the plates on opposite sides of the material, one of said plates having portions extending beyond the plane of the plate, and a guide having a rounded rope receiving surface and pivoted in said portion, so as to oscillate therein according to the tension of a rope passing through the said guide.

80

In testimony whereof I affix my signature.
LEONIDAS E. JEFFERSON.
